UNITED STATES PATENT OFFICE

THOMAS W. N. HILLIARD, OF MERIDEN, CONNECTICUT, ASSIGNOR, BY MESNE ASSIGNMENTS, TO CONNECTICUT TELEPHONE & ELECTRIC CORPORATION, OF MERIDEN, CONNECTICUT, A CORPORATION OF DELAWARE

SIGNAL LIGHT

Application filed August 2, 1928. Serial No. 296,874.

My invention relates to a signal device, supporting means. A gas luminescent tube is secured to the base 5 and the ends of the tube connected to the terminals 6-6. The base 5 may be made to fit standard types of sockets or other connecting devices suitable for use in connection with gas luminescent tubes. For use in connection with signal systems, I prefer to make the gas luminescent tube of such form that it presents substantially the same appearance from whichever angle it may be viewed. The tube is preferably formed of one or more helical convolutions 7, and the end of the tube forming the last convolution preferably extends down through the center of the convolutions, as indicated at 8. The lower ends 9 of the tube, as heretofore indicated, are connected to the contacts or terminals 6-6, heretofore mentioned. A transparent protecting globe or bulb 10 is preferably secured to the base 5.

It is one of the objects of my invention to produce a gas luminescent lamp suitable for general use, and capable of convenient use like an ordinary electric lamp.

It is a further object to provide an improved gas luminescent tube light assembly which will reduce danger of accident due to the comparatively high tension line heretofore employed in connection with gas luminescent lights.

It is still a further object to provide a fire-alarm or other signal system including a signal light which may be controlled by the supervisory circuit of the fire-alarm or other signal system.

Other objects will be apparent as the specification proceeds.

In the drawings which show, for illustrative purposes only, one preferred form of the invention—

Fig. 1 is a diagrammatic view of a fire-alarm system involving features of the invention;

Fig. 2 is a diagrammatic view of a plurality of signal lights serving a fire-alarm or other system;

Fig. 3 is an enlarged detail sectional view through an improved gas luminescent lamp and transformer assembly.

An improved form of gas luminescent tube as shown more particularly in Fig. 3 will first be described. I provide a base 5, which may be of any suitable construction and carries terminals or contacts 6-6 for engagement with the terminals of a socket or other

The unit thus far described may be sold and handled as such, and the connections to a suitable source of current readily made. The use of my improved gas luminescent light unit obviates the difficulty heretofore encountered in making the wire connections to gas luminescent tubes as heretofore made.

In most situations, such as in connection with signal systems of various kinds, it is not practical to run the comparatively high tension lines required for the operation of gas luminescent tubes between relatively remote units, and I therefore propose to provide a transformer in a housing to which my improved gas luminescent lamp may be directly connected. Thus, the high tension lines for operation of the lamp are reduced to a negligible length, and the danger in connection with the carrying of high tension lines through a signaling box and streets is obviated.

In the preferred form shown, I provide a transformer designated generally 11, supported in a transformer housing 12. The potential of the low tension lines 13 is stepped

up by means of the transformer 11 to the extent sufficient to operate the gas luminescent lamp. As shown the secondary or high tension lines 14—14 are short and terminate in 5 suitable terminals 15—15 secured preferably to an insulating plate 16 which may form a cover for the transformer housing. The insulating plate 16 in the form shown is provided with apertures for receiving the contacts 10 or terminals 6—6 of the gas luminescent lamp.

If desired, the ring 17 which supports the plate 16 may be supported upon the housing 12 and provided with a screw socket for the 15 reception of the threaded end of a protecting globe 18. The part 17 may also support any suitable type or protector or screen 19 for the protection of the globe 18 and gas luminescent lamp. The transformer housing 20 12 is preferably provided with a suitable connection such as a threaded socket 20 to be received and supported by a nipple or pipe 21, indicated diagrammatically in Fig. 1.

When my improved lamp is to be used in 25 connection with a signaling system as shown in Figs. 1 and 2, the gas luminescent lamp may be supported on a pipe or tube 21 above the signal box 22, which is in turn supported from the usual base or pedestal 23, or which 30 may be supported from overhead in any position. The low tension line 13 may be an ordinary lighting circuit, and is connected to the primary of the transformer, as will be plain. In some cases it will be desirable 35 to have all of the gas luminescent signal lamps connected and controllable from a single point by a simple switch as would be possible in connection with the form shown in Fig. 2. It may also be desirable to have 40 each lamp controlled by means such as a relay at each station in connection with signal systems. It is usual to have a supervisory circuit for the remote control of fire-alarm mechanism in a fire-alarm box at 22, and the 45 gas luminescent lamp relay control may be actuated or controlled by such supervisory circuit.

In connection with such a system I employ 50 a relay designated generally 24, which makes and breaks connection to the primary of the transformer. The relay 24 is controlled by the supervisory circuit designated generally 55, and which in the fire-alarm system controls fire-alarm mechanism forming no part of the present invention and not disclosed. The supervisory circuit includes a source of current 26, a switch 27, a switch 28, and a resistance 29. By closing the switch 27, the 60 resistance 29 is short-circuited and the relay 24 closed so that the gas luminescent lamp will then be lighted. As soon as the relay has been closed, the switch 27 may be opened and with the switch 28 closed, the potential 65 will be reduced, but not sufficiently to open the relay 24. In order to break the relay 24,

the switch 28 is opened, thus further reducing the potential by putting more of the resistance 29 into the circuit, and the relay 24 is then broken. The fire-alarm devices controlled by the supervisory circuit are such that when the supervisory potential is reduced sufficiently to break the relay 24, the fire-alarm mechanism will not be affected. This is one means only and other systems of remote control will readily suggest themselves.

While the invention has been described in some detail and for illustration in connection with a fire-alarm system, it is to be observed that the invention is of broader application and the improved gas luminescent light and associated parts may be advantageously employed in other situations, for example, in connection with police re-call systems, traffic light systems, landing fields, and similar places where the present type of light would be advantageous.

The particular gaseous agent in my improved tube may vary according to requirements. For example, I may employ neon, 90 neon and argon, neon and mercury vapor, or in fact any gas which is capable of producing the desired lighting effect.

Various changes and modifications may be made within the scope of the invention as defined in the appended claims.

I claim:

1. A luminescent gas lamp construction comprising a housing, an insulating support detachably mounted upon the housing and having passages extending therethrough, a step-up transformer suspended from said support within said housing, contacts secured to said support within said housing, a relatively irrefrangible detachable lamp base having a relatively fragile tube containing a luminescent gas and having rigid terminal prongs projecting from the base at fixed distances from each other so as to extend within said passages and be positioned by the walls thereof and to engage said contacts, said tube being entirely outside of said housing.

2. A luminescent gas lamp construction comprising a base ring having a globe seat, a housing secured to said base ring, an insulating supporting member secured to said base ring and having passages for prongs, a transformer mounted within said housing, output contacting terminals connected therewith within said housing, and a relatively irrefrangible detachable lamp base having rigid terminal prongs insertable through said passages into engagement with said contacts and a tube containing luminescent gas with electrodes connected to said prongs.

3. A luminescent gas lamp construction comprising a housing, an insulating support, means for securing the periphery of said support to said housing, a transformer mounted in said housing, contacts carried by said sup-

port and directly connected to the output leads of the transformer, said support having passages leading to said contacts and a detachable lamp comprising a base with terminal prongs projecting therefrom and adapted to enter said passages in order to engage said contacts and a gas-filled tube carried by said base with its ends connected to said prongs.

10 4. In a luminescent gas lamp construction, the combination comprising a housing, an insulating top member, means for supporting said top member upon said housing, contacts carried by said top member, a step-up transformer having a frame suspending it from said insulating member and having its output terminals connected to said contacts, said insulating top member having passages for conductive prongs of a gas lamp base to enter therein.

15 5. A luminescent gas lamp construction including an inferior housing provided with an outwardly extending flange at its upper rim, an insulating member substantially covering said housing at its top, a superior ring fastened to said flange and supporting said insulating member, a voltage raising transformer giving potentials upwards of 1000 volts and mounted within said inferior 20 housing dependent from said insulating member, current conductor leads to said transformer, contact members mounted upon said insulating member and connected to the high 25 potential output of said transformer, and apertures in said insulating member for the 30 passage therein of the conductive prongs of a luminescent gas lamp base.
